No. 705,950.

Patented July 29, 1902.

A. MURINICK.
INCANDESCENT GAS BURNER.

(Application filed Nov. 21, 1900.)

(No Model.)

UNITED STATES PATENT OFFICE.

ALEXANDRE MURINICK, OF ST. PETERSBURG, RUSSIA.

INCANDESCENT GAS-BURNER.

SPECIFICATION forming part of Letters Patent No. 705,950, dated July 29, 1902.

Application filed November 21, 1900. Serial No. 37,815. (No model.)

To all whom it may concern:

Be it known that I, ALEXANDRE MURINICK, a subject of the Czar of Russia, residing in the city of St. Petersburg, Russia, have invented 5 certain new and useful Improvements in Incandescent Gas-Burners, of which the following is a specification.

This invention relates to incandescent burners, and is more particularly intended for use 10 with burners for street illuminating. Its main object is to secure the incandescent mantle against shocks and jars. This is obtained, as hereinafter more fully described, by the aid of a springy chamber arranged be- 15 tween the gas-inlet and the burner, said chamber serving the double purpose of deadening shocks and jars and supplying the gas with air in such a manner that an intimate mixture is initiated from the first moment the 20 gas and air meet each other.

Another object is to provide means for adjusting the gas-inlet into said springy chamber by turning the latter, together with the burner.

25 In the accompanying drawings the burner is shown in connection with a street-lamp.

Figure 1 is a longitudinal section; Fig. 2, a cross-section of the regulator on an enlarged scale, and Fig. 3 a detail view.

30 The gas-pipe *a* carries a cone *b*, which is provided with a channel *c*, standing in communication with the pipe *a* and provided in a portion of its periphery with a groove *d*. (Shown in dotted lines.) The cone *b* is closely 35 fitted in a housing *e*, which is provided with two channels *f* and *g*. The channel *c* serves, on the one hand, for conducting the gases to the burner, and, on the other hand, to permit any suitable fluid—for example, alcohol—to 40 be introduced through the channel *f* into the gas-pipe in the event that the latter should become frozen. The groove *d* is in communication with the channel *g*, the pipe *h*, and the coil *i*, which latter carries the well-known 45 igniting-burner, which is omitted from the drawings. The housing *e* has screwed upon it a cap *k*, the interior of which is conically shaped. Upon this cap *k* is screwed the gas-feed regulator. The latter consists, as will 50 be better seen from Fig. 2, of a short inner tube *l*, having a perforated bottom, in the center of which is fixed a needle *m*, and an outer

tube *o*, having a top plate with a central opening *x* of conical shape for the needle to project through, so that an annular passage is 55 formed, through which the gas is fed into the mixing-chamber. The tube *o* is screwed with its internally-threaded lower portion on the externally-threaded lower portion of the tube *l*, so that the area of the gas-feed opening *x* 60 can be widened or reduced by screwing the tube *o* to a higher or lower position.

To the upper end of the tube *o* is secured, in the manner hereinafter described, a springy chamber, which carries the burner and serves 65 the combined purpose of mixing the gas with air and guarding the mantle from shocks. The chamber is composed of concentrically-arranged upper cup-like shells *rt* of annular shape, which are secured at their upper narrow opening to a ring *p'* and with their lower wider opening directed downward to receive in the space between their lower edges the upper edge of a lower shell *s* of similar shape, which is fastened at its lower narrow opening to a 70 ring *p*², said rings *p'* and *p*² being connected with each other by outwardly-bent flatsprings *p*, fixed with their upper ends to the ring *p'* and with their lower ends to the ring *p*². The ring *p*² is internally threaded and screwed on the 75 externally-threaded upper end of said tube *o*. The ring *p'* is internally threaded to receive and hold the burner-tube *u* and the parts connected therewith. By this construction the 80 mixing-chamber is made available for consuming shocks without interfering with the proper admission of air. Moreover, the air to be mixed with the gas is sucked into the chamber by the gas-jet all around the latter through the annular opening formed by the 85 shells *r* and *s*, and then it is caused to pass up and down toward the lower edge of the inner shell *t*, whereby the current of air is caused to gradually contract, so as to take the 90 shape of a cone, which is axially traversed by the gas-jet, so that the molecules of air impinge against the gas-jet under an oblique angle in any point of its circumference. In 95 this manner a very intimate mixture of the air and gas is initiated from the first moment they touch each other.

Surrounding the supply-pipe *a*, near the bottom of the lamp, is located a second pipe *y*, to which the housing *e* is secured by an

arm *l*, which can be turned by means of a lever 4. There is further arranged on the base *z* a washer 2, as also a spiral spring 3. This arrangement serves the purpose of compensating for expansion and contraction of the feed-pipes, due to changes of temperature.

By grasping the lever, the pipe *a* remaining stationary, the housing *e* can be so turned through the medium of said lever that the channel *c* will coincide with *f* and gas pass into the latter. If the cone closes the channel *f*, a small portion only of the gas escapes to the small pipe *i*.

Gas entering the channel *f* passes through the channel *g* and from this to the regulator, then flows through the openings *n* to the nozzle *x*. After the gas has left the nozzle *x* an intimate mingling of air with the gas takes place in the manner described and the mixture formed reaches the incandescent mantle, where ignition takes place from the igniting-flame, which may burn constantly at a very slight expense.

The following is what I claim and desire to secure by Letters Patent:

1. In an incandescent burner the combination with the feed-opening for the gas-supply and the burner, of a chamber for mixing the gas with air, said chamber being constructed with concentrically-arranged upper cup-like shells secured at their upper narrow edges to a ring for receiving the burner and leaving spaces between their wider lower edges, lower

shells of similar shape which are connected with their lower narrow edges to a ring closely surrounding the gas-inlet and project with their upper wider edges into the spaces left between the lower edges of the upper shells, and outwardly-bent springs connected at their ends with said rings, substantially as and for the purpose stated.

2. In an incandescent burner the combination with the cone fixed to the gas-supply pipe, the housing rotatably mounted upon said cone, and the gas-channels formed in the cone and housing, of a gas-chamber formed by the upper part of the housing, a conically-hollowed plug screwed into the top part of the housing and having a centrally-bored axially-arranged extension on top, a hollow cylinder screwed on said extension and having a perforated bottom and open top, a needle axially fixed within the hollow of the cylinder, and another hollow cylinder adjustably mounted upon the first-named cylinder and having a conical opening in its top for said needle to project through, substantially as and for the purpose stated.

In testimony that I claim the foregoing as my invention I have signed my name in presence of two subscribing witnesses.

ALEXANDRE MURINICK.

Witnesses:

PAUL SCHULT,
GUSTAV LEHMANN.
